UNITED STATES PATENT OFFICE.

AUGUST BRUN, OF CHICAGO, ILLINOIS.

LIFE-BOAT APPARATUS.

972,809.

Specification of Letters Patent. Patented Oct. 18, 1910.

Application filed June 29, 1909. Serial No. 505,076.

To all whom it may concern:

Be it known that I, AUGUST BRUN, a subject of the King of Norway, residing at Chicago, in the county of Cook and State 5 of Illinois, have invented certain new and useful Improvements in Life-Boat Apparatus, of which the following is a specification.

My invention relates to a life boat, or the like, and apparatus for supporting and 10 launching the same, and has for its object to provide certain new and improved constructions and arrangements in devices and apparatus of this character.

One of the principal objects of the invention is to provide means whereby a life boat 15 may in an emergency be almost instantly launched. The usefulness of the life boats carried upon vessels is very frequently impaired by the fact that so much time is required in getting the boats in the water.

My invention provides means whereby the boat may be launched within a few seconds after the occasion has arisen for launching it, and moreover, while the vessel on which 25 the life boat is carried is still in motion. When life boats are hung from davits, as is customary at the present time, the vessel has to be practically stopped before the boats can be lowered.

30 A further object of the invention is to so construct the launching means that it may be put in operation by those in the life boat.

A further object is to provide a supporting and launching means for the boat which 35 is rotatable so that the boat will normally lie parallel with the rail of the vessel, thus obstructing the deck of the vessel as little as possible, but may be turned with its forward end over the rail of the vessel at any 40 angle to the vessel that may be desirable.

A further object of the invention is to provide a construction of life boat which will be suitable for being so launched.

The invention has for further objects such 45 other new and improved constructions in life boats and in apparatus for supporting and launching the same as will be described in this specification and particularly set forth in the claims appended hereto.

50 The invention, in a preferred embodiment, is illustrated in the accompanying drawings, wherein—

Figure 1 is a side elevation of the boat and its supporting and launching apparatus. 55 Fig. 2 a plan view of the latter devices with

the boat removed. Fig. 3 a sectional view on line 3—3 of Fig. 2, looking in the direction of the arrows. Fig. 4 a section on line 4—4 of Fig. 2. Fig. 5 a rear end view of the apparatus. Fig. 6 a sectional plan taken on line 6—6 of Fig. 5. Fig. 7 a sectional view on line 7—7 of Fig. 6, looking in the direction of the arrows. Fig. 8 a vertical sectional view illustrating the means employed for releasing the launching or ejecting device, and Fig. 9 a vertical section taken on line 9—9 of Fig. 1.

Like characters of reference indicate like parts in the several figures of the drawings.

Referring now to the drawings, 15 represents the life boat which is preferably completely covered and inclosed by the deck 16, provided with openings which may be closed by the slide doors 17, 17. The hull of the boat is preferably made of steel and the 75 upper part of aluminum. In order that the rudder 18 and propellor 19 may be protected from injury due to the shock of launching, the stern of the boat is recessed, the rudder and propeller being located in this recess. The keel 20 of the boat is extended under and rearwardly of these parts as shown at 21. Preferably, the propeller has 80 but two blades diametrically arranged so that they can be made to stand in upright 85 position when the boat is not in use. The boat may be propelled by any suitable form of motor. It may be provided with the usual cork belt 22.

I have shown what I consider a suitable 90 construction of life boat, having in mind the manner, hereafter to be described, in which it is to be launched. It is obvious, however, that my invention is not limited to the particular form of boat, and the construction 95 of the latter may differ considerably, according to the circumstances in which it is to be used.

Preferably, the boat is supported upon a frame work which is mounted so as to rotate 100 and the forward end of which is capable of downwardly inclination. For example, referring particularly to Figs. 1, 2 and 9, I provide a standard 23, the base of which 24 may be bolted to the deck 25 of the vessel. On the stationary top 26 of the standard rests a rotatable plate 27 keyed to a shaft 28, the lower end of which is provided with a collar 29 held, but rotatably, between the plates 30 and 31 by suitable bolts. Bolted 110

to the plate 27, which constitutes a turn-table, are the channel beams 32, 32. Attached to, or integral with the beams 32 are the uprights 33, to which are attached the 5 rails 34, 34, one on each side of the boat. These parts constitute the supporting means for the boat. Preferably, grooved rollers 35 are mounted on the beams 32. The keel of the boat rests upon these rollers. The rails 10 34 are preferably provided with the rollers 36.

I prefer to provide at the forward end of the supporting means thus described, a similar frame which, while normally remaining 15 in horizontal position, is capable of inclination. Beams 37, 37 are hinged to the beams 32, 32 by the pivot 38 (Fig. 3), and a lever 39 arranged in the space between the oppositely placed beams is fulcrumed on the same 20 pivot and is connected at its forward end by pivot 40 to the forward beams 37, and carries at its rear end the counter-weight 41, provided with the sector-gear 42. A gear wheel 43 mounted between beams 32 meshes 25 with sector 42. A handle 44 is rigidly connected with the gear wheel. The beams 37 are provided with the uprights 45 which support the rails 46, 46, alining with rails 34, 34. The beams 37 are provided with 30 rollers 35, as in the case of beams 32 and the rails 46 with the rollers 36. At the forward end of beams 37 is preferably a roller 47. A stop 41^a engaged by the counter weighted 35 part 41 limits the inclination of the forward sector to about twenty degrees.

The launching or ejecting device is preferably mounted so as to travel on the rear ends of beams 32 and is preferably operated by spring pressure.

40 48 is a casing formed with the webs 49, 49 (Figs. 1, 5 and 7) which extend under the upper web of beams 32. In order to decrease friction, rollers 50 may be mounted in the under side of casing 48; and if desired, 45 the rollers 51 may be set into the webs 49 on axles 49^a so as to run on the under surface of the upper webs of beams 32. The forward end of casing 48 is provided with the follower 52 conformed to the contour of the 50 stern of the boat.

Within the casing are mounted the two windlasses 53, 53, provided with the gears 54, 54 between and meshing with which is the gear 55 rigid on the stem 56, which stem 55 is provided with the hand-wheel 57. Keyed to stem 56 is a ratchet 58, and a dog 59 for the ratchet is pivoted to the plate 60 on the end of the casing. The cables 61, 61 connected with the springs to be described hereafter, 60 pass through the hollow arms 62, 62 on casing 48, and are wound upon the windlasses 53.

Connected with the forward end of beams 32 are the cylindrical spring casings 63, 63, one of these being shown in longitudinal 65 section in Fig. 4. Within each of these cas-

ings is a very strong spiral spring 64 anchored to the end of the casing and attached at the other end to a plunger follower 65. The cables 61 are suitably connected with this follower and the corresponding one on 70 the other side of the apparatus.

From the back plate 66 of casing 48 projects a concaved web 67 in the upper surface of which is formed the forward notch 68 and the rearwardly placed notch 69. A 75 handle 70 forked at 71 is connected by shaft 72 to the web 67 and connected with this handle by guides 73, 73 is a squared rod 74, the end of which is adapted to extend into the notches 68 or 69. A flat spring 75 is 80 attached to the upper end of rod 74 and bears against the handle 70. The space between the rod and the handle is sufficient so that when the spring is flattened out against the handle, rod 74 will rise out of the 85 notch in web 67. A cord 76 may be attached to the end of rod 74 and lead into the interior of the boat through the perforation 77 in the deck. On the squared portion 78 of the shaft 72 connecting the forks of handle 90 70 is a detent 79 which engages with a plate 80 which is set between beams 32, 32. When the rod 74 is in the slot 69, the detent 79 engages with the stop plate 80. When rod 74 is in slot 68 the detent is turned 95 out of the path of the stop plate. Cushioned stops are preferably provided to limit the forward movement of the launching or ejecting device. Preferably, I provide on each side of the boat an air cylinder 81 attached to beam 32 and having a plunger 82 which is engaged by casing 48. The deck 100 16 of the boat should be provided with the glass covered port holes 83 and the ventilating jacks 84. Rings 85 may be provided by 105 means of which the boat can be hoisted in the usual way.

The operation of the apparatus above described is as follows: Under ordinary circumstances the life boat will be supported 110 on the deck so as to lie parallel with the rail. The springs 64 will be kept under tension, the tension being regulated by means of the hand-wheel 57. The squared rod 74 connected with handle 70 will be in the rear 115 notch 69 so that the engagement of detent 79 with the stop plate 80 holds the ejecting or launching device, consisting of the follower 52, casing 48 and associated parts, in the rearward position, as shown in Fig. 1. 120 If a motor boat is used, it will be operated by a motor which can be started instantly. Now if occasion arises for launching the life boat, for example, if a man falls overboard, the persons whose duty it is to operate the life boat get into the boat at once, closing shutters 17 after them. By pulling on the cord 76, the rod 74 is drawn out of slot 69 and the tension of springs 64 thrusts 125 the ejecting device against the stern of the 130

boat, causing the latter to move forward upon the rollers. As soon as the weight of the boat is brought to bear upon the tilting forward end of the supporting means, 5 the latter tilts downwardly and the boat slides over the rail into the water. It will be understood that before the men who operate the life boat have gotten inside they will have turned the life boat at the proper angle, 10 or this may be done by others on board the vessel. If the vessel is in motion, the life boat should be turned about so that it can be launched, as nearly as may be, in the direction from which the vessel is traveling. 15 The boat is strongly built so that it will stand the shock of the launching. The rudder and propeller, the parts most easily broken, are protected by the extended portion 21 of the keel. The ejecting device is stopped and 20 cushioned against the cushioning devices 81, 82.

On the return of the life boat, it may be hoisted up in the usual way, replaced on its support, which may be turned back to its 25 normal position, parallel with the rail of the vessel after the forward or tilting end has been lifted into alinement with the rear portion of the supporting frame by means of handle 44. The ejecting device will, of 30 course, be reset.

I do not limit myself to the particular devices, constructions and arrangements shown and described, as modifications might be devised which would come within my 25 invention as defined by the claims. I have described the life boat apparatus as it is intended to be used upon a vessel, but it is obvious that the same form of supporting and launching apparatus might be used 40 for launching a boat from a pier or dock. While I consider the boat herein shown and described as being the most suitable in view of the manner in which it is to be launched, the apparatus might be used in connection 45 with boats of different description.

I claim:

1. In life boat launching apparatus, the combination with a boat, of a supporting device which supports the keel and the sides 50 of the boat and holds said boat in substantially horizontal position, an ejecting device which is movably mounted on said supporting device so as to engage one end of said body, and means for moving said 55 ejecting device so as to force said boat lengthwise of said supporting device and eject the same therefrom.

2. In life boat launching apparatus, the combination with a boat, of a supporting device which supports the keel and the sides 60 of the boat and holds said boat in substantially horizontal position, an ejecting device which is movably mounted on said supporting device so as to engage one end of 65 said boat, and means for moving said eject-

ing device, comprising a spring, so as to force said boat lengthwise of said supporting device and eject the same therefrom.

3. The combination with a boat, of a supporting device for the same on which it is supported so as to be capable of movement lengthwise, a spring operated ejecting device adapted to engage with one end of the boat by means of which the boat may be moved from said supporting device, and means for adjusting the tension of the spring element of said spring operated device. 70 75

4. In life boat launching apparatus, the combination with a boat, of a supporting device which supports the keel and the sides of the boat and holds said boat in substantially horizontal position, an ejecting device which is movably mounted on said supporting device so as to engage one end of said boat, means for moving said ejecting device comprising a spring, so as to force said boat lengthwise of said supporting device and eject the same therefrom, and releasing means for said ejecting device. 80 85 90

5. The combination with a boat of a supporting device for the same on which it is supported so as to be capable of movement lengthwise, a spring operated ejecting device adapted to engage with one end of the boat by means of which the boat may be moved from said supporting device, and releasing means operable from inside the boat for releasing said spring operated device. 95

6. In life boat launching apparatus, the combination with a boat, of a supporting device provided with rollers which support the keel and with rollers which bear against the sides of the boat, said supporting device holding said boat in substantially horizontal position, an ejecting device which is movably mounted on said supporting device so as to engage one end of said boat, and means for moving said ejecting device so as to force said boat lengthwise of said supporting device and eject the same therefrom. 100 105 110

7. In life boat launching apparatus, the combination with a boat, of a supporting device provided with rollers which support the keel and with rollers which bear against the side of the boat, said supporting device holding said boat in substantially horizontal position, an ejecting device which is movably mounted on said supporting device so as to engage one end of said boat, means for moving said ejecting device so as to force said boat lengthwise of said supporting device, and locking means for said ejecting device which is adapted to be released when said boat is to be launched. 115 120 125

8. The combination with a boat, of a supporting device for the same on which it is supported so as to be capable of movement lengthwise, said device comprising a rear section substantially horizontal on which 130

the boat normally rests and a forward section hinged to the rear section so as to be capable of downward inclination; and means for moving said boat from the rear section of the supporting device to the hinged forward section, for the purpose described.

9. The combination with a boat, of a supporting device for the same on which it is supported so as to be capable of movement lengthwise, said device comprising a rotatable rear section on which the boat normally rests and a forward section hinged to the same so as to be capable of downward inclination; and means for moving said boat from the rear section of the supporting device to the hinged forward section, for the purpose described.

10. The combination with a boat, of a supporting device for the same on which it is supported so as to be capable of movement lengthwise, a movable ejecting device which engages the stern of the boat, and means located forwardly of the same on each side of the boat for imparting movement to said ejecting device.

11. The combination with a boat, of a supporting device for the same on which it is supported so as to be capable of movement lengthwise, a movable ejecting device which engages the stern of the boat and springs at each side of the boat for imparting movement to said ejecting device.

12. The combination with a boat, of a supporting device for the same on which it is supported so as to be capable of movement lengthwise, spring cylinders located on the supporting device at each side of the boat, springs in said cylinders, a follower which is movably mounted on the supporting means and engages the stern of the boat, and cables connecting the follower with said springs.

13. The combination with a boat, of a supporting device for the same on which it is supported so as to be capable of movement lengthwise, spring cylinders located on the supporting device at each side of the boat, springs in said cylinders, a follower which is movably mounted on the supporting means and engages the stern of the boat, cables connecting the follower with said springs, a casing on said follower, windlasses in said casing on which said cables are wound, and means for rotating said windlasses.

14. The combination with a boat, of supporting means for the same comprising a standard, a rear supporting section rotatably mounted on the standard which is substantially horizontal and which normally supports the boat, and a forward section hinged to the rear section so that it is capable of forward inclination.

15. The combination with a boat, of sup-

porting means for the same comprising a standard, a rear supporting section rotatably mounted on the standard which is substantially horizontal and which normally supports the boat, a forward section hinged to the rear section so that it is capable of forward inclination, and rollers on said supporting means over which the keel of the boat travels.

16. The combination with a boat, of supporting means for the same comprising a standard, a rear supporting section rotatably mounted on the standard which is substantially horizontal and which normally supports the boat, a forward section hinged to the rear section so that it is capable of forward inclination, rollers on said supporting means over which the keel of the boat travels, and rollers on said supporting means which engage the sides of the boat.

17. The combination with a boat, of supporting means for the same comprising a standard, a rear supporting section rotatably mounted on the standard which is substantially horizontal and which normally supports the boat, a forward section hinged to the rear section so that it is capable of downward inclination, the rear end of said forward section being counter-weighted, a segment gear on the forward section, and a gear having a handle on the rear section, whereby the said forward section may be returned to its horizontal position.

18. In life boat apparatus, the combination with a life boat, of supporting means for the same comprising a standard, a rear supporting section rotatably mounted on the standard, a forward section hinged to the rear section so as to be capable of downward inclination; and a launching device comprising a follower which engages the stern of the boat and is movable upon said rear supporting section, springs arranged on said supporting means, cables attached to said springs, means connected with said follower upon which the cables may be wound, a stop on said supporting means, a movable detent connected with said follower, and a releasable lock which holds said detent in engagement with said stop.

19. The combination with a boat, of supporting means for the same comprising a standard, a rear supporting section which is rotatably mounted on the standard and which is substantially horizontal and normally supports the boat, and a forward tilting section which is counterweighted so as to be held normally in horizontal position; and means which engages the boat and moves the same from said rear supporting section upon the forward section, for the purpose described.

20. The combination with a boat, of supporting means for the same comprising a standard, a rear supporting section rota-

tably mounted on the standard, which is substantially horizontal and which normally supports the boat and a forward tilting section; and means for moving the boat from 5 said rear section upon said tilting section, for the purpose described.

21. The combination with a boat, of supporting means for the same comprising a standard, a rear supporting section rotatably mounted on the standard, which is substantially horizontal and which normally 10

supports the boat, and the forward tilting section; and a spring-operated ejecting device on the rear section which engages with the stern of the boat and moves it from said 15 rear section upon the forward section, for the purpose described.

AUGUST BRUN.
